US00D827655S

(12) **United States Design Patent** (10) Patent No.: **US D827,655 S**
 Wang et al. (45) Date of Patent: ** Sep. 4, 2018

(54) **DISPLAY SCREEN WITH GRAPHICAL USER INTERFACE**

(71) Applicant: **Tencent Technology (Shenzhen) Company Limited**, Shenzhen, Guangdong (CN)

(72) Inventors: **Chong Wang**, Guangdong (CN); **Bei Zhang**, Gaungdong (CN); **Guie Zhuge**, Guangdong (CN); **Cuixia Li**, Guangdong (CN); **Ying Peng**, Guangdong (CN); **Bei Li**, Guangdong (CN); **Chuming Tang**, Guangdong (CN)

(73) Assignee: **Tencent Technology (Shenzhen) Company Limited** (CN)

(**) Term: **15 Years**

(21) Appl. No.: **29/546,733**

(22) Filed: **Nov. 25, 2015**

(30) **Foreign Application Priority Data**

May 26, 2015 (CN) 2015 3 0163046

(51) LOC (11) Cl. **14-04**

(52) U.S. Cl.

USPC **D14/485**

(58) **Field of Classification Search**

USPC D14/485-495
CPC G06F 17/211; G06F 17/212; G06F 3/1251;
G06F 3/0481; G06F 2203/04807

(57) **CLAIM**

The ornamental design for a display screen with graphical user interface, as shown and described.

DESCRIPTION

FIG. 1 is a front view of a first embodiment of a display screen with graphical user interface showing our new design; and,

FIG. 2 is a front view of a second embodiment of a display screen with graphical user interface showing our new design.

The broken lines showing an electronic device illustrate environmental structure, whereas the broken lines showing a display screen and elements of the graphical user interface illustrate portions of the article. No subject matter illustrated in broken lines form part of the claimed design.

1 Claim, 2 Drawing Sheets
